Patented Apr. 7, 1914.

UNITED STATES PATENT OFFICE.

JAMES LYNAM, OF NEWMAN, CALIFORNIA.

FOUNTAIN-BRUSH AND CAN.

1,092,656.

Specification of Letters Patent.

Patented Apr. 7, 1914.

Application filed March 7, 1913. Serial No. 752,720.

To all whom it may concern:

Be it known that I, JAMES LYNAM, citizen of the United States, residing at Newman, in the county of Stanislaus and State 5 of California, have invented certain new and useful Improvements in Fountain-Brushes and Cans, of which the following is a specification.

My present invention relates to improvements in combined oil cans and brushes and more particularly to that type of oil can carrying a brush so arranged that the brush head forms a closure for the can, and the object of my invention is to improve the construction and increase the efficiency of a combined can and brush of the above described character.

More particularly my present invention is an improvement over the structure of 20 combined can and brush disclosed in my copending application, Serial No. 694,193.

One of the primary objects of this invention is to provide the brush head with a valve controlling the flow of oil or other liquid contained in the can to the brush and so arranged that the application of a cap employed in protecting the brush when the latter is not in use will automatically close the valve and prevent all leakage of 30 oil to the brush irrespective of the position of the can. And a still further object of my invention is to so arrange the valve construction as to avoid all catching or binding of the cap and valve either when applying or removing the cap.

With these and other objects in view, my invention will be more fully described, illustrated in the accompanying drawing, and then specifically pointed out in the claims 40 which are attached to and form a part of this application.

In the drawing:—Figure 1 is a front elevation of my can and brush construction, showing the cap in raised position, the portions of the structure illustrating my present invention being shown in section and the valve being shown in open position; Fig. 45 2 is a central vertical sectional view of the brush and can construction shown in Fig. 1, but with the cap in position on the can and the valve consequently closed; Fig. 3

is a fragmentary sectional view on the line 3—3 of Fig. 1, showing certain details in the valve construction.

Corresponding and like parts are referred to in the following description and indicated in all the views of the drawing by the same reference characters.

As the construction of the entire device, with the exception of the valve, is practically the same as that of my copending application above referred to, but a brief description of the same is necessary.

The oil receptacle or can 10 is provided with a brush 11, the head of which forms a closure for the can and with a detachable cap or cover 12 which, when the device is not in use, serves to protect the brush and also to shut the same off from exposure to the air and thus prevent its becoming 70 gummed with dried oil. The can is preferably formed of relatively light sheet metal and in any shape, certain of its walls being provided with resilient diaphragms 13 either formed integrally with the walls or set into 75 the same as shown, these diaphragms being adapted to buckle inwardly under pressure to force the oil from the receptacle in the usual well known manner. The can is provided at its upper end with a cylindrical 80 discharge spout 14 threaded as at 15 to receive the threaded annular flange 16 carried by the brush head. Secured to the top of the can and extending in spaced relation about the spout, is a threaded annular flange 85 17 to receive the threaded flange 18 of the cap 12.

The brush 11 includes a brush head 19 of any suitable form or construction, the bristles being preferably set in the head by 90 cement or in some other suitable manner to prevent all leakage of oil through the head. The brush head is provided centrally with a discharge opening or port 20 through which oil may pass from the can to the brush 95 and this port is closed, under normal conditions by a valve 21. The valve comprises a substantially rectangular plate of sheet metal slidably mounted in a horizontal recess 22 formed in the brush head and intersecting 100 the opening 20 at its inner end. This recess is preferably exactly equal in width and

thickness to the width and thickness of the valve plate and the plate is further guided in its movement in and out of the recess, and said movement limited by a pin 23 which is 5 passed through the brush head and through a slot 24 formed in the valve plate. This pin and slot are so arranged that the valve plate may be moved inwardly to completely close the opening 20 and that the valve plate may 10 also be moved outwardly a sufficient distance to fully expose the opening 20 shown in Fig. 1. The outer end of the valve plate is provided with an upwardly directed extension 25 having an inbent terminal 26, the 15 extension 25 and terminal 26 forming in effect an operating head for the valve. As shown in Fig. 2 of the drawing, this valve plate, together with its operating head, is so arranged and proportioned that if, when the 20 valve is opened as shown in Fig. 1, the cap is positioned over the brush and moved downwardly to engage with the threaded collar 17 its threaded flange 18 will engage first against the inbent terminal 26 and then 25 against the extension 25 of the valve plate and because of its inclination and the inclination of said extension and terminal, force the valve plate inwardly to close the valve, as shown in Fig. 2. Furthermore, the 30 cap will constantly bear against the extension 25 of the valve plate when in place and will therefore hold the valve in closed position, irrespective of the position in which the can is placed, preventing all leakage of oil to 35 the brush.

From the foregoing description, it will be apparent that I have provided an extremely simple form of valve structure and one which, at the same time, is of great value, 40 due to the fact that with this valve construction the can is rendered non-leakable and may be readily packed in a suit case or trunk or if the device is used in oiling automobile covers or other portions of vehicles it may be 45 packed in any position in a tool box carried by the vehicle without danger of injury to other articles contained therein. It will however be understood that I do not wish in any way to limit myself to the specific 50 details of construction illustrated and described as various minor changes may at any time be made without in the slightest degree departing from the spirit of my invention as set forth in the appended claims.

55 If deemed advisable additional pins 23' may be passed through the brush head, one upon either side of the slotted portion of the valve plate, to insure the proper movement of the valve plate. If the brush head is of 60 that type formed of plastic material cast in one piece these pins will not be necessary, but if the head is built up of two or more layers of wood, rubber or other material and the valve plate inserted between certain of

these layers, the additional pins will be 65 found necessary.

The space between the flanges 14 and 17 collects any oil running back in the brush when the device is in upright position and prevents the same from running over the 70 outside of the can to the inconvenience of the person using the same.

Having thus described the invention, what is claimed as new is:

1. In a combined can and brush of the 75 type in which the brush head forms a closure for the can, a valve slideable transversely in the brush head, and a cap applicable to the can to protect the brush and close the valve.

2. In a combined can and brush of the 80 type in which the brush head forms a closure for the can, a valve slideable transversely in the brush head having an operating head extending beyond the brush head when the 85 valve is opened, and a cap adapted for engagement with the can to inclose the brush and proportioned to engage the valve head when moved into position and to so close the valve.

3. An oil applying device including an oil 90 can having a discharge opening, a brush acting as a closure for said opening, the head of the brush being in turn provided with an opening, a valve plate movable across the 95 opening and extending beyond the brush head when the opening is exposed, and a cap adapted to be positioned about the brush and detachably secured to the can, said valve plate being so arranged that when in extended position the application of the cap 100 will force the valve plate inwardly across the opening.

4. An oil applying device including an oil can having a discharge opening, a brush, the head of which acts as a closure for said 105 opening, the head of the brush being provided with an opening, a valve plate slidably mounted in the brush head and movable across the opening, said valve plate being provided at its outer end with an upwardly 110 and inwardly directed terminal which in open position of the valve extends outwardly beyond the side of the brush head, and a cap adapted for detachable engagement with the can and having a flared flange which, 115 upon application of the cap, engages against the upwardly and inwardly directed terminal of the valve plate to force the same inwardly and across the brush opening.

5. An oil applying device including an oil 120 can having a discharge opening, a brush acting as a closure for said opening, the head of the brush being in turn provided with an opening, a valve plate movable in a recess formed in the brush head to close the opening when in innermost position, said valve plate being provided with a longitudinal slot, a pin passed through the brush head 125

and slot to limit the movement of the valve plate, an upwardly and inwardly directed terminal carried by the free end of the valve plate and extending in spaced relation to the brush head when the valve is opened, and a cap adapted for detachable engagement with the can about the brush and having a flaring flange which engages

against said valve terminal during application of the cap to close the valve. 10

In testimony whereof I affix my signature in presence of two witnesses.
